Inventor

Joseph Monaco

UNITED STATES PATENT OFFICE

JOSEPH MONACO, OF NEW YORK, N. Y.

INDOOR CLOTHESLINE EXTENSION

Application filed March 2, 1932. Serial No. 596,330.

This invention relates to an indoor clothes line extension and has for an object to provide an improved clothes line extension whereby the clothes may be attached to the line by clothes pins in the usual way with the line extending inwardly through the window and then, when the clothes hanging operation is completed, the clothes line may be swung about to extend only outside of the window allowing the window to be closed.

A further object of this invention is to provide an improved clothes line extension which will make for increased safety of the person hanging the clothes, making it unnecessary to lean out of the window to hang the clothes.

Still a further object of this invention is to provide an improved clothes line extension which may be pivoted to extend either inside 20 or outside of the window at will.

Yet another object of this invention is to provide an improved clothes line extension which is easily adjustable to vary the tension 25 on the clothes line without the necessity of leaning out of the window.

Still another object of this invention is to provide an adjusting means for clothes line extensions which is easily accessible and easily operable.

With the foregoing and other objects in view, as will hereinafter become apparent, this invention comprises the constructions, combinations and arrangements of parts, hereinafter set forth, disclosed and shown on the accompanying drawing. In this drawing,

Figure 1 is a side elevation showing the device applied to the window.

Figure 2 is a top plan view.

Figure 3 is a sectional view taken on line 3-3 of Figure 1, and

Figure 4 is a diagrammatic view illustrating the arrangement of the pulleys.

There is shown at 10 a diagrammatical representation of a window jamb provided with the usual path 11 for the window 12. Secured to the window jamb 10 by means of the screws 13 is a bracket 14 having an arm 15 extending at an angle thereto, the angle being approximately 45° more or less. The

arm 15 ends in a boss 16 which may be corrugated on the top, as shown at 17, the arm 15 being of sufficient length so that the boss 16 will be beyond the plane 18 of the outside of the window jamb 10. Supported on the boss 16 is a bracket arm 19, the bracket arm 19 having a boss 20 complementary to the boss 16 and held thereto by a thumb locking bolt 21 projecting through the bottom of the boss 16 into the boss 20.

As will be apparent, by tightening down the thumb locking bolt 21, the boss 20 is immovably fixed on the boss 16, but when the locking bolt 21 is loosened the arm 19 on boss 20 may be swung around through a substantial angle. The bracket arm 19 ends in a U-shaped clamp 22, the clamp 22 being provided for holding a pulley rod 23. To allow the pulley rod 23 to be easily adjusted along its length, the U-clamp 22 is provided with a pair of roller bearings 24, a lock set screw 25 being provided through the bottom of the clamp 22 for securing the pulley rod 23 against movement except when desirable. The pulley rod 23 has a U-shaped groove 26 provided at one side thereof to receive the clothes line 27, the groove 26 being aligned with a pulley 28 at the outside end of the pulley rod 23 and another pulley 29 at the inside end of the pulley rod 23, U-members 30 being provided at each pulley for holding the clothes line 27 thereagainst.

A third pulley 31, supported in any suitable manner as on a clothes line pole at a distance from the pulleys 28 and 29, serves to support the clothes line 27 in operative position with the clothes holding portion as at 32.

In operation, the window 12 will be open in the position shown in Figure 1, and the pulley rod 23 extended within the window jamb 10 in the position shown in full lines in Figures 1 and 2. When all the clothes have been hung on the line and it is desired to close the window, the thumb locking bolt 21 is loosened and the bracket 19 turned about through the position shown in dotted line in Figures 1 and 2 until the inner pulley 29 is far enough out of the window jamb to allow the window 12 to be closed, the thumb locking bolt 21 being then tightened to hold it in this

position. If it be desired to increase or decrease the tension on the clothes line, the lock screw 25 may be loosened, allowing the pulley rod 23 to be moved in the desired direction 5 against the roller 24 in the U-clamp 22 of the bracket arm 19. Rings 33 are secured to the U-members 30 to act as finger holds in adjusting the position.

The novel features and the operation of 10 this device will be apparent from the foregoing description. While the device has been shown and the structure described in detail, it is obvious that this is not to be considered limited to the exact form disclosed 15 and that changes may be made therein within the scope of what is claimed without departing from the spirit of the invention.

Having thus set forth and disclosed the nature of this invention, what is claimed is:

20 1. A clothes line extension comprising a bracket member, an arm extending angularly therefrom, a bracket arm pivotally adjustable on said angular arm, a holding member on said bracket arm, a pulley rod passing through said holding member, means for adjustably securing said bracket arm to said angular arm, means for adjustably securing said pulley rod in said holding member, a clothes line groove formed along one side of 25 said pulley rod, a pulley member on each end of said pulley rod, and a U-member secured to said pulley rod at each pulley member, said U-member serving to hold the clothes line in position thereon.

30 35 2. An indoor clothes line extension comprising a bracket member, means for securing said bracket member to a window jamb, an arm integrally projecting from said bracket member at an angle thereto, a corrugated boss formed on the end of said angular arm, a bracket arm, a boss on said bracket arm complementary to said corrugated boss on said angular arm, means for adjustably securing said bosses together, a U-clamp on 40 45 said bracket arm, a pulley rod, roller means in said U-clamp allowing said pulley rod to pass therethrough, means for securing said pulley rod at any desired position within said U-clamp, and means on said pulley rod for supporting the clothes line.

50 55 60 65 3. An indoor clothes line extension comprising a bracket member, means for securing said bracket member to a window jamb, an arm integrally projecting from said bracket member at an angle thereto, a corrugated boss formed on the end of said angular arm, a bracket arm, a boss on said bracket arm complementary to said corrugated boss on said angular arm, means for adjustably securing said bosses together, a U-clamp on said bracket arm, a pulley rod, roller means in said U-clamp allowing said pulley rod to pass therethrough, means for securing said pulley rod at any desired position within said U-clamp, means on said pulley rod for

supporting the clothes line, said means comprising a pulley at each end of said pulley rod, a U-member secured to said pulley rod at each pulley, and a groove formed on one side of said pulley rod to receive the clothes line.

In testimony whereof I affix my signature.
JOSEPH MONACO.
